Primary Examiner — Jack Reickel*Assistant Examiner* — Michael A Kervin(74) *Attorney, Agent, or Firm* — Wood Herron & Evans LLP(57) **CLAIM**

I claim the ornamental design for a leveler table, as shown and described.

DESCRIPTION

FIG. 1 is a front right perspective view of a leveler table according to the present invention.

FIG. 2 is a front view of the leveler table shown in FIG. 1. FIG. 3 is a rear view thereof.

FIG. 4 is a left side view thereof, the right side being a mirror image thereof.

FIG. 5 is a cross-sectional view thereof, taken on line 5-5 of FIG. 6.

FIG. 6 is a top view of the leveler table shown in FIG. 1; and, FIG. 7 is a bottom view thereof.

The broken line showing of a leveler table is for the purpose of illustrating portions of the article and forms no part of the claimed design.
